UNITED STATES PATENT OFFICE

BERNIS M. SHIPLEY, OF DAYTON, OHIO, ASSIGNOR TO THE NATIONAL CASH REGISTER COMPANY, OF DAYTON, OHIO, A CORPORATION OF MARYLAND

CASH REGISTER

Application filed July 13, 1928. Serial No. 292,435.

This invention relates to cash registers and analogous machines, and more particularly refers to improvements in adding and subtracting totalizers for such machines.

As illustrated herein, the invention is embodied in a machine of the type disclosed in Letters Patent of the United States, No. 1,242,170, issued October 9, 1917, to F. L. Fuller; No. 1,619,796, issued March 1, 1927, to Bernis M. Shipley, and No. 1,761,542, January 3, 1930, to Bernis M. Shipley.

One object of this invention is to provide an adding and subtracting totalizer of the type disclosed, with novel mechanism for supplying a single unit (known in the art 15 as the fugitive "1") to the totalizer wheel of lowest order when the totalizer is overdrawn.

Another object is to supply the so-called "fugitive 1" on the totalizer wheel of the lowest order when the totalizer is overdrawn 20 in either direction, that is, from positive to negative, or from negative to positive.

Another object of the invention is to equip a machine having an adding and subtracting 25 totalizer, with a novel means for compelling the operator to take the total from that set of adding or subtracting totalizer wheels containing the correct balance.

With these and incidental objects in view, the invention includes certain novel features 30 of construction and combinations of parts, the essential elements of which are set forth in appended claims and a preferred form or embodiment of which is hereinafter described 35 with reference to the drawings which accompany and form a part of this specification.

Of said drawings:

Fig. 1 is a sectional view of the machine taken to the right of and looking toward the 40 units bank of keys.

Fig. 2 is a fragmentary view of the total control lever, showing particularly the manner in which this lever controls the interlock which enforces the selection of the proper 45 totalizer in totaling operations.

Fig. 3 is a fragmentary view of a part of the transfer mechanism of the units bank showing the means for tripping the transfer device when an overdraft occurs to supply the 50 fugitive "one".

Fig. 4 is a detail side view of the interlocking mechanism between the adding and subtracting totalizers, and the "add" and "subtract" keys.

Figs. 5, 6 and 7 are detail views of parts 55 of the interlocking mechanism shown in Fig. 4.

Fig. 8 is a detail view of the mechanism operated by the totalizer wheel of highest order for tripping the transfer device in the 60 units bank when an overdraft occurs on the totalizer, and for controlling the interlocking mechanism to enforce the selection of the proper totalizer in total-taking operations.

Fig. 9 is a fragmentary view of a part of 65 the tripping device.

Fig. 10 is a top plan view, partly in section, taken on lines 10—10, Fig. 13.

Fig. 11 is a detail view of one of the positive totalizer wheels. 70

Fig. 12 is a detail view, showing the means to restore the units transfer stop arm to normal set position.

Fig. 13 is a view looking in the direction of the arrows on line 13—13 of Fig. 4, and 75 shows the adding and subtracting totalizer, partly broken away to show the wheels of the highest and lowest orders, together with the means for tripping the transfer device in the units bank by the wheel of the highest 80 order when an overdraft occurs.

General description

This invention, for convenience, is applied to an adding and subtracting totalizer of the 85 type illustrated and described in the patents and the application referred to above, the invention residing in part, in the provision of a device to automatically cause a single unit to be added into the units totalizer wheel 90 when an overdraft occurs and during the same operation on which the overdraft occurs, thus insuring that the totalizer will register the correct amount at the termination of the operation. 95

The novel totalizer selecting and the rectification of the overdraft features are included in a machine substantially the same as that disclosed in the above referred to co-pending application, and enough of the for- 100

mer construction is shown herein to convey a full understanding of the present invention, reference being made to the prior patents and application cited for a more complete disclosure of those elements which do not form a part of the present invention.

Keyboard

The machine includes a keyboard having 10 a plurality of banks of amount keys 40 (Fig. 1), depression of which sets up the amounts to be added onto, or subtracted from, the adding and subtracting totalizer 104, 105, and which are to be accumulated on any of the 15 other totalizers with which the machine may be provided.

Only the units bank of amount keys 40 (Fig. 1), and the "add" and "subtract" keys 41 and 42 respectively, (Fig. 4), which control the adding and subtracting totalizer, are shown herein.

Amount keys

The amount keys 40 (Fig. 1) are of the 25 usual type of depressible keys provided in machines of this character. Each row of amount keys is mounted in a key frame 43 supported in the machine by cross rods 44 and 45, extending between the right side 30 frame 46 (Fig. 13) and the left side frame 47 (Figs. 1 and 13) of the machine.

The keys 40 cooperate with a locking detent bar 48 supported at its upper and lower ends by links 49 and 50 pivoted on the key 35 frame 43.

Depression of a key 40 cams the detent bar 48 downwardly until a shoulder 51 on the key wipes past a stud 52 on the detent, whereupon a spring, not shown, returns the detent 40 bar to its normal position, with the stud 52 over the shoulder 51 on the key to lock the latter in its depressed position.

Near the end of each adding or subtracting operation of the machine, the depressed keys 45 40 are released by a rocking release shaft 53 having a plurality of arms 54 fast thereon, which support a rod 55.

The release shaft 53, when rocked counter-clockwise (Fig. 1), presses the rod 55 against 50 the tails formed on the free ends of the links 49 supporting the upper ends of the detent bars 48 to cam the links 49 clockwise about their pivots. The links 49 shift the detent bars 48 downwardly to release the depressed 55 keys. Springs (not shown) then restore the keys 40 to their home positions.

The keys 40 of each amount bank control their respective denominational zero stop pawl 60 (Fig. 1), the purpose of which is to 60 arrest the corresponding differential actuator 62, associated with each bank of keys when no key in the row is depressed. Depression of a key in any amount row or bank rocks the corresponding zero stop pawl 60 counter-clockwise to its ineffective position

by means not shown herein, but fully disclosed in the above-mentioned patents and application.

Amount differential mechanism

The differential mechanism associated 70 with each of the amount banks of keys actuates the totalizers to accumulate thereon the various amounts set up by depression of the amount keys, and, differentially adjusts various other elements, such as indicators, printing elements, etc., none of which are shown herein inasmuch as they form no part of the present invention. The differential mechanism also functions in total taking operations, 80 and at such times, is controlled as to its advance by the totalizer wheels.

This differential mechanism is identical 85 with the differential mechanisms illustrated and described in the above mentioned patents and application, wherefore only a brief description thereof will be given.

The differential mechanism for each denomination includes a differentially movable member comprising a pair of substantially 90 circular disks 62 and 63, between which are mounted in peripherally spaced relation a number of segmental actuating racks 64, 65 and 66 corresponding with the number of lines of totalizers in the machine. The disks 62 and 63 are fast on a hub 67 journaled on a stud 68 supported by hangers 69 and 70, which in turn, are supported on cross rods 71 and 72 extending between the side frames 46 and 47 of the machine. A link 74 and a bell crank 75 pivotally support a latch 73 on the differentially adjustable member 62, 63, which latch releasably connects the differentially adjustable member 62, 63 with an invariably movable driving segment 76 also pivoted on the stud 68. A spring 77 holds the foot of the latch 73 in engagement with a shoulder (not shown) on the skeletonized drive segment 76. A pair of cams 78 pinned to a drive shaft 79 rock a bell crank lever 80 pivoted on the hanger 70. A link 81 connects the upper end of the lever 80 with the driving segment 76. The cams 78 make one complete rotation in clockwise direction at each operation of the machine to impart a constant excursion to the drive segment 76, first clockwise, and then counter-clockwise to normal position. On its clockwise movement, the drive segment 76 carries with it the latch 73 and the differentially movable member 62, 63 until the forward arm of the bell crank 75 contacts the inner end of a depressed key, or the zero stop pawl 60 in those banks wherein no keys have been depressed, whereupon the bell crank 75 rocks counter-clockwise about its pivot and disconnects the latch 73 from the drive segment 81. Such disconnection of the latch 73 enters the nose thereof into one of a plurality of notches 82 formed in a serrated bar 83 supported on the cross rod 72

110 115 120 125 130

and the upper end of the hanger 70, to lock the differential in its adjusted position while the drive segment 76 completes its clockwise travel.

5 On its return, an inner face (not shown) of the drive segment 76 contacts a stud 84 in the disks 62 and 63 to restore the differential to its normal position.

10 A beam 90, the forward end of which is pivoted to the differentially adjustable actuator 62, 63, is slotted at its rear end to embrace a stud 91 intermediate the ends of a differential link 92. As the differential actuator 62, 63 is positioned under control of the 15 amount keys 40, the end of the beam 90 which is pivoted thereto, is also positioned, after which a roller 93 on the bell crank lever 80 contacts the lower edge of the beam 90, during the operation of the machine, to complete 20 the adjustment of this beam, and consequently adjust the differential link 92.

The upper end of each differential link 92 positions its aligning segment 94 on a shaft 96, and the lower end of each link positions 25 its arm 95 journaled on a shaft 97.

30 A spiral segment gear 101 fast on the arm 95 meshes with a spiral pinion 102 pinned to a printer shaft 103 for the purpose of adjusting the corresponding printing element (not shown).

After the totalizer actuator racks 64, 65 and 66 have been advanced to correspond with the value of the amount keys depressed, the selected totalizer, or totalizers, are moved 35 into engagement therewith. The actuators 62, 63 are then returned counter-clockwise to their normal positions at the same time rotating the denominational totalizer wheels a number of steps commensurate with the value 40 of the amount keys 40 depressed, to thereby accumulate on the totalizer the amount set up on the keyboard.

The totalizer selecting mechanism and the mechanism for engaging and disengaging the 45 totalizers with the actuators are not illustrated or described herein, but are fully disclosed in the above-mentioned patents and application, to which reference is made for a complete explanation thereof.

50 Totalizers

There are three lines of totalizers in the present machine. Two of these lines, the front and the back lines, have ten totalizers 55 on each line, consisting of a plurality of interspersed adding wheels journaled on a tube.

As these totalizers are fully illustrated and described in the above-mentioned patents, no further description thereof is thought necessary for an understanding of the present invention.

The third or upper totalizer line supports a single adding and subtracting totalizer comprising a plurality of pairs of wheels (Figs. 65 1, 11 and 12), each pair including a positive

wheel 104 and a negative wheel 105 (Fig. 13), spaced apart and rotatably mounted on a totalizer shaft 106. Only the pinions of the highest order and of the lowest order are shown herein. Two intermediate bevel pinions 107 (Fig. 11) loose on the opposite ends of a pin 108 projecting diametrically through the shaft 106 between the spaced wheels 104 and 105, of each pair mesh with bevel gears 109 and 110 fast on the positive and the negative totalizer wheels 104 and 105, respectively, to couple like denominational wheels of the adding and subtracting totalizer together in such a manner that when a denominational wheel of one pair is rotated in one direction, the remaining wheel of the pair will be rotated the same number of steps in the opposite direction. Collars 111 fast on the outer ends of the pins 108 retain the intermediate pinions 107 in place.

70 The totalizer shaft 106 is mounted in end frames 112 (Figs. 3 and 13) and 113 (Figs. 8, 9 and 13) which depend from and are slideable along a supporting shaft 115. A rod 114 extends between the frames to afford rigidity and to properly space them apart. This rod 114, the totalizer shaft 106, and the end frames 112 and 113 form a frame for the adding and subtracting totalizer 75 slideable longitudinally on the supporting shaft 115.

90 A rod 120 (Figs. 8, 10 and 13) extending downwardly from the frame 113 carries an anti-friction roller 121 embraced between the walls of a channel formed in a drum cam 122. This drum cam is journaled on a stud in the side frame 47 and is differentially adjusted under control of the "add" key 41 (Fig. 4) and the "subtract" key 42 to shift the adding, subtracting totalizer axially along the shaft 115, to position the adding wheels 104 or the subtracting wheels 105 opposite the single set of actuators 62, 63 common to both sets of adding and subtracting wheels. The differential mechanism controlled by the "add" key 41 and the "subtract" key 42, for adjusting the totalizer shifting cam 122 to select the adding or subtracting side of the totalizer, is identical with the differential mechanism disclosed in the inventor's co-pending application referred to above, to which reference is 100 made for an explanation thereof, and is not 105 shown herein.

110 The rod 120 shifts with the adding and subtracting totalizer and is guided, with respect to the shaft 115, by a slot 146 in a bracket 147 (Figs. 10 and 13), secured to the left side frame 47. The upper part of the roller 121 lies in the slot 146. This bracket also prevents the totalizer frame from turning about the shaft 115.

115 As shown in Figure 13, the drum cam 122 is in the position to which it has been adjusted under control of the "subtract" key 42 (Fig. 4). Therefore, the negative totalizer wheels 105 are in line with the totalizer actuator 120 130

racks 64. When the drum cam 122 is adjusted under control of the "add" key 41 (Fig. 4), the totalizer frame is slid to the left, as viewed in Fig. 13, to position the positive totalizer wheels 104 in line with the totalizer actuators 64.

When the negative wheels 105 are turned in adding direction by the actuating racks 64, the corresponding positive wheels 104 10 will be turned backwardly to like extents.

The foregoing construction is old and only constitutes a part of the present invention in so far as it is combined with the new and novel features now to be set forth.

25 *Fugitive one mechanism*

During an operation of the machine, if an amount greater than the amount on the positive wheels 104 is to be subtracted therefrom, 20 the remainder will be a negative balance. When this happens an overdraft is said to occur. This negative balance will, ordinarily however, be short of the correct amount by "one".

25 To correct the totalizer so that the appropriate side will register the correct amount after an overdraft has occurred, mechanism is provided, in the present machine, for automatically adding a single unit onto the totalizer wheel of lowest order during the operation in which the overdraft occurs.

The invention is effective to supply the "fugitive one" in the event the overdraft occurs by subtracting a larger amount from 35 a smaller amount already registered on the positive side of the adding and subtracting totalizer, or by adding a larger amount to a smaller amount already registered on the negative side of the adding and subtracting totalizer.

35 The operator in registering positive and negative amounts on the adding and subtracting totalizer will depress the "add" key 41 to accumulate the positive amounts on the adding wheels 104 of the totalizer, and will 5 depress the "subtract" key 42 to accumulate negative amounts on the subtracting wheels 105.

The "add" and "subtract" keys 41 and 42 40 control mechanism not herein shown, to rock the drum cam 122 (Fig. 13) in one direction or the other, whereby to shift the adding and subtracting totalizer along the shaft 115 to bring the adding wheels 104, or the subtracting wheels 105, into alinement with the single set of actuators 62, 63 common to both the sets of wheels 104, 105. Thereafter the positive and negative amounts set up on the amount keys 40 are added onto the corresponding set of wheels.

Normally the adding and subtracting totalizer is assumed to be "clear", that is, the adding wheels 104 of a machine having a capacity of seven denominations, will register 65 0,000,000 while the subtracting wheels

105, which ordinarily register the complement less "one" of whatever amount is carried on the adding wheels, will stand at 9,999,999.

Accumulation of amounts on the adding 70 wheels 104 operates through the pinions 107 to decumulate on the subtracting wheels 105, and vice versa. That is, the adding of an amount to either set of totalizer wheels, will reversely rotate the remaining set of totalizer wheels to directly subtract a similar amount therefrom, except where the amount added is sufficient to transform the balance from positive to negative, or vice versa.

In the art, this transformation of balance is 80 known as "passing through zero" and is accomplished by adding an amount on the negative side which is in excess of the amount registered on the positive side, or by adding an amount on the positive side which is 85 greater than the balance registered on the negative side.

Assuming that the operator starts with the positive totalizer cleared, as above set forth, and wishes to enter the following items

+ 54	96
- 96	12
+ 12	30

the proper balance will be

On a machine not equipped with this invention, he will first depress the "add" key 41 to set the totalizer selecting mechanism (not shown) so that upon operation of the machine, the adding and subtracting totalizer 104, 105 will be slid along the supporting shaft 115 to bring the adding wheels 104 in line with the actuators 62, 63.

He will also depress the proper amount keys 40 to set up the item "54" and operate the machine, whereupon the item "54" will be accumulated on the adding wheels 104 of the adding and subtracting totalizer so that at the end of the operation the two sides of the totalizer will register

Adding side	0,000,054
Subtracting side	9,999,945

It will be noted that the wheels 105 of the subtracting side of the totalizer register an amount which is the complement less "1" of the amount registered by the adding wheels 104.

The operator will then depress the "subtract" key 42 to set mechanism which, upon operation of the machine, will slide the adding and subtracting totalizer along the shaft 115 to bring the subtracting wheels 105 in line 120 with the actuators 62, 63, and will also depress amount keys 40 representing the item 96, and operate the machine.

At the end of this operation, the positive and negative wheels of the adding and sub-

tracting totalizer will register amounts as follows:

Adding wheels..... 9,999,958
Subtracting wheels..... 0,000,041

5 Here it will be noted that the subtracting wheels register "one" less than the true result, and that the adding wheels register "one" less than the true complement of that amount registered on the subtracting wheels.

10 To add the final item "12", the operator again depresses the "add" key 41, and the amount keys 40 representing the amount "12", and operates the machine. At the end 15 of such operation, the positive and negative sides of the adding and subtracting totalizer will register the following amounts:

15 Adding wheels..... 9,999,970
Subtracting wheels..... 0,000,029

20 The true balance should be "-30", but the subtracting wheels register "one" less than the true balance, while the adding wheels register "one" less than the complement of the amount registered on the subtracting wheels, and as the totalizer is concealed, the operator does not know whether he has a positive or negative balance, and hence does 25 not know on which side of the totalizer he should add the "fugitive one".

25 Heretofore, the "fugitive one" has been supplied at the end of the entry of all the items, but it obviously would be the better 30 plan to contrive means which would cause the totalizer to register the true balance at any point in the operation of entering amounts.

30 To obtain this result, a transfer mechanism for the units bank is provided, and means contrived to trip such units transfer mechanism each time the balance "passes through zero" in either direction, the invention residing in the novel means employed to trip the transfer mechanism for the units totalizer 35 wheels 104, 105.

40 A transfer segment 125 (Fig. 1) formed on the outer end of an arm 119 pivoted at 176 between the disks 62 and 63 of the units differential lies in the same vertical plane with the actuator rack 64, and is adapted to be 45 latched to the actuator rack 64 when the units differential rocks clockwise out of its normal position in the following manner.

45 A square stud 126 carried by the head of a latching lever 127 pivoted on the units transfer segment 125, normally rests against the end 128 of a transfer stop arm 129 pivoted on the stationary supporting hanger 69, to normally hold the transfer segment 125 in the 50 position shown in Figure 1, in which the segment 125 is spaced apart from the adjacent end of the actuator rack 64 against the tension of a spring 130 connected to the head of the latching lever 127. The spring 130 constantly urges the lever 127 in a counter-clock-

wise direction about its pivot on the segment 125.

55 A recessed projection or holder 132 is mounted to travel with the differential member 62, 63, the tail of the lever 127 having a stud 131 normally engaging the projection 70 above its recess 177.

60 Clockwise movement of the differential member 62, 63 closes the gap between the actuator rack 64 and the transfer segment 75 125, which is yieldingly held against movement by the spring 130 until contact of the rack 64 therewith. As soon as this occurs, the spring 130 rocks the latching lever 127 counter-clockwise and moves the stud 131 80 on the tail of such lever, into the recess 177 of the projection 132 which advances with the differential member 62, 63 and relatively to the lever 127. The lever 127 thus latches the transfer segment 125 to the actuator rack 85 64, so that the actuator rack and the transfer segment now move as a unit.

65 When the differentials have been arrested under control of the depressed keys, the 90 wheels 104 or 105 of the selected side of the adding and subtracting totalizer are engaged with their respective actuator racks 64, after which the actuator racks are restored to their normal positions. As the units differential member 62, 63 on its return, as heretofore explained, approaches the position shown in Fig. 1, the square stud 126 on the latching levers 127 strikes the end 128 of the transfer stop arm 129, which arrest causes the lever 127 to rock clockwise about its pivot on the 100 units transfer segment 125 to unlock the segment 125 from the differential rack 64. The transfer segment 125 is now held in the position shown in Fig. 1, by contact of the stud 126 with the transfer stop arm 129, and the 105 differential continues its movement to its normal position.

70 A flat stud 135 (Figs. 1 and 3) on a catch 136 fast on a stub shaft 139, normally engages a shoulder 137 formed intermediate 110 the ends of a slot 138 in the transfer stop arm 129 to hold the stop arm 129 in the position shown, with the end 128 thereof in the path of the square stud 126, against the tension of a spring 133 connected to the transfer stop arm. Releasing the catch 136 from the shoulder 137 frees the transfer stop arm 129 to the 115 action of its spring 133, which rocks the stop arm in clockwise direction (Fig. 3) to remove the end face 128 of the stop arm from the path of the stud 126 on the latching lever, and thus enable the transfer segment 125 (Fig. 1) to accompany the segmental rack 64 as the latter completes its return to home 120 position. This, in effect, lengthens the rack 64 so as to impart a single extra step of movement to whichever units wheel, 104 or 105, may at that time be in engagement with the 125 rack 64.

75 The upper end wall of the slot 138 in the 130

catch 136 contacts, and is arrested by, the pin 135 in the catch to limit the clockwise travel of the transfer stop arm.

That the units wheel shall be turned but a single additional step, the transfer stop arm 129 carries a shoulder 134 (Fig. 3) located behind the end face 128, which shoulder is brought into the path of travel of the stud 126 on the latching lever 127 when the end face 128 is removed therefrom.

At the beginning of the next operation, the actuator 62, 63, carrying the rack 64, advances in clockwise direction (Fig. 1), the rack 64 forcing the transfer segment 125 and the transfer latching lever 127 ahead of it, so that the stud 126 of the latching lever rides towards the end face 128 of the transfer stop arm 129 until it finally escapes past the end of the stop arm 129, which is then free to be restored to its normal position.

The means which restores the units transfer stop arm is identical with that which is shown in the patents and application heretofore mentioned to restore the transfer stop arms therein shown, and comprises a restoring spider 149 (Fig. 12) journaled on the hollow stud 68 concentrically with the actuator 62, 63 and the driving segment 76.

A stud 1149 on one arm of the restoring spider 149 extends laterally into the path of a face 85 on a suitably journaled driving segment 86 identical with the units driving segment 76 and located to the right thereof.

Cams 87 on the drive shaft 79 rock a lever 88 connected by a link with the driving segment 86 to rock the latter.

As the driving segment 86 approaches the end of its initial or clockwise stroke, the face 85 thereof strikes the stud 1149 on the spider 149 to rock the latter and cause an arm 1490 thereof to strike the depending body of the transfer stop arm 129 and rock the stop arm counter-clockwise to restore the stop arm to normal, against the tension of the spring 133.

The stop arm 129, on its return to normal, brings the intermediate shoulder 137 of its slot 138 above the stud 135 of the catch 136 whereupon a coiled spring 141 (Fig. 1) encircling the stub shaft 139, snaps the pin 135 of the catch 136 beneath the shoulder 137 of the slot 138 to retain the stop arm with its end face 128 in the path of the stud 126.

The stub shaft 139, to one end of which the catch 136 is secured, is rotatably mounted in the supporting hanger 69, a trip pawl 140 being pinned to the other end of the stub shaft. The spring 141 coiled about the stub shaft 139 and having one end secured to a stud 142 in the trip pawl 140 and the other end anchored to the supporting hanger 69, constantly urges the pawl 140 and the catch 136 in clockwise direction.

Obviously the special carry when tripped to add "1" to the units wheel of the adding set of totalizer wheels 104, will simultane-

ously subtract a like amount from the subtracting set of totalizer wheels 105, or vice versa, thus supplying the "fugitive one", so that the totalizer always registers the correct balance at the end of each of those operations of the machine during which the balance changes from positive to negative, or vice versa, the bevel pinion connection between the members of each pair of like denominational wheels facilitating this result with the use of a single transfer mechanism.

To trip the units transfer mechanism at the proper time, a control disk 116 (Figs. 8, 9 and 13) from which projects a radial tripping tooth 117, is rigidly connected by a sleeve 118 to the adding wheel 104 of highest order, to turn therewith.

The tripping tooth 117 coacts with a projection 180 or 184 on the respective members of a pair of laterally spaced arms 164, 166 journaled on the opposite ends of a stud 165 mounted in a flange 148 (Figs. 10 and 12) formed on and extending transversely of the free end of the slotted guide bracket 147.

The arms 164 and 166 lie on opposite sides, respectively, of the flange 148. A reversing gearing connects the arms 164, 166 including gears 167, 171 secured to the hubs 168, 172 of the respective arms 164 and 166, and meshing with their respective wide pinions 169 and 173, separately journaled on pins projecting from the flange 148, the pinions also being of sufficient width and so located as to mesh with each other.

This reversing gearing so couples the arms 164 and 166 that when either of the arms is rocked downwardly, it will actuate the reverse gearing to swing the remaining arm upwardly.

The control disk 116 with its tripping tooth 117 shifts axially with the adding and subtracting totalizer, so that when the subtracting wheels 105 of the totalizer are in line with the common actuators 62, 63, the control disk 116 and its tooth are located in line with the arm 164, as shown in Fig. 13. When the totalizer is shifted to bring the adding wheels 104 into line with the actuators, the control disk 116 and its tooth shift therewith to locate the disk and tooth in line with the arm 166.

When the totalizer is moved into engagement with the actuator racks 64, by mechanism well known in the art, which is not described herein, reference being made to the above mentioned patents therefor, the tripping tooth 117 is moved into co-operative relation with either the arm 164 or the arm 166, depending upon which set of totalizer wheels 104 or 105 is selected for engagement with the actuator racks 64.

If, after the negative totalizer wheels 105 have been shifted into engagement with the actuator racks 64, an amount, as "96", greater than the amount, as "54", already registered

on the positive wheels, is accumulated on the negative wheels, the positive wheels 104 are turned backwardly past their "zero" positions to their "9" positions. As the positive wheel 104 of the highest order (Fig. 13) passes from its "zero" to its "9" position, the tooth 117 (Fig. 8) on the disk 116 rigidly connected thereto, turns in clockwise direction and wipes over the finger 180 projecting upwardly from the arm 164 to cam this arm downwardly in clockwise direction. The arm 164, through the train of reversing gears, rocks the arm 166 upwardly in counter-clockwise direction. The arm 164, carries a lateral stud 163 on its free end, embraced by a slot in a bell crank 161 pivoted at 162 on the flange 148 of the guide bracket 147. As the arm 164 rocks downwardly in clockwise direction it rocks the bell crank lever 161 counter-clockwise to swing the arm 181 thereof from the full-line position shown in Fig. 8, to the dotted-line position there shown.

A transmitting shaft 151 journaled in ears forming part of the totalizer and frames 112, 25 113 (Figs. 3, 8, 9 and 13) carries an arm 159 at that end adjacent the totalizer of highest value, which arm extends into proximity to the bell crank lever 161 and is provided with studs 160 disposed one on each side thereof.

Since the transmitting shaft 151 shifts axially with the adding and subtracting totalizer, it is necessary to provide these oppositely projecting studs 160 so that one or the other thereof will enter the path of the arm 181 of the bell crank 161 depending upon which side of the adding and subtracting totalizer is alined with the common actuators 62, 63.

When the totalizer is engaged with the actuators, the appropriate stud 160 on arm 159 enters the path of the arm 181 of the bell crank 161, as indicated by dotted lines in Fig. 8, so that as the adding wheel 104 of highest order with its disk 116 turns reversely through zero, to cause the tooth 117 of the disk to rock the bell crank 161, the arm 181 of the bell crank wipes the stud 160 on the transmitting shaft 151 to rock the shaft in counter-clockwise direction.

A second arm, 150 (Figs. 3 and 13), is fast on the shaft 151 at a point adjacent the units actuator 62, 63, the arm being forked to embrace a pin 152 on a disk 145 journaled on the totalizer shaft 106, and held in position by a collar 175 fast on the shaft.

When the totalizer is engaged with the actuators 62, 63, a tripping tooth 144 on the tripping disk 145 normally assumes a position (shown in dotted lines, Fig. 3) adjacent an ear 143 on the free end of the tripping arm 140 fast on the stub shaft 139 which supports the catch 136.

A spring 153 (Fig. 3) connected to a stud 154 on the arm 150 and to a stud 155 on the totalizer end frame 112, normally holds the

shaft 151, with its arms 150 and 159, and the tripping disk 145 in the positions shown in Figure 3. The spring 153 also restores these parts to their normal positions near the end of the operation. The stud 155 (Fig. 3) limits the clockwise movement of the arm 150 and consequently of the shaft 151 and its arm 159.

Immediately after the arm 181 (Fig. 8) has passed the stud 160 and has assumed the position shown by dotted lines, the spring 153 (Fig. 3) rocks the arm 150 and shaft 151 clockwise until the arm 150 is arrested by the stud 155. This restores the shaft 151, its appended mechanism and the disk 145 to their normal positions. A stud 182 on a spring-urged pawl 183 (Fig. 8) cooperates with either of two notches formed in the bell crank lever 161 to aline said lever in either of its two positions.

Assuming, as heretofore, that the tripping tooth 117 has wiped over the finger 180, depressing the arm 164 and raising the arm 166 through the reversing gear, the arms remain in such positions, being held against accidental displacement by the engagement of the pawl 183 with a notch in the bell crank 161, until during some subsequent operation of the machine, the adding totalizer wheel 104 of highest denomination passes through zero in the opposite direction, whereupon the arm 181 of the bell crank which has remained in the dotted line position shown in Fig. 8, will be restored to the full line position shown in such figure, during which travel it will rock the shaft 151 against the tension of its returning spring 153 (Fig. 3) to again trip the units transfer mechanism.

Referring to Fig. 3, the tripping tooth 144 on the substantially circular lever 145 is brought to the position shown by dotted lines, as the totalizer wheels are engaged with the actuator racks 64. Now, when the shaft 151 is rocked counter-clockwise by the tooth 117 as just described, it also rocks the arm 150 counter-clockwise, and, due to the pin and slot connection 152, rocks the lever 145 clockwise about the shaft 107. On this clockwise movement, the tooth 144 on the lever 145 wipes the ear 143 on the pawl 140 to rock this pawl, the stub shaft 139 and the tripping arm 136 counter-clockwise to remove the stud 135 on the trip arm 136 from the shoulder 137 on the transfer stop arm 129, whereupon the spring 133 rocks the transfer stop arm 129 clockwise until it is arrested by contact of the upper wall of the slot 138 with the stud 135, in which position the shoulder 134 is in the path of the square stud 126 on the latch lever 127.

Now, as the actuators 62, 63 return to their normal positions while the totalizer wheels are engaged therewith, the transfer segment 125 for the units denomination is permitted

- to continue its counter-clockwise movement one step further, or, until the square stud 126 contacts the shoulder 134 on the arresting lever 129, which arrests the units transfer segment. When this occurs, the latching lever 127 rocks clockwise to disengage its stud 131 from the projection 132 on the units actuator. At this time, the transfer segment 125 has moved one additional step 10 in a counter-clockwise direction, and has thereby advanced the negative totalizer wheel of the units order one step to accumulate thereon the single unit known as the "fugitive 1".
- 15 The negative totalizer wheels now register the correct negative balance.
- An example of the above operation will now be given to assist in the comprehension of the mechanism involved.
- 20 Since the wheels 105 forming the subtracting side of the adding and subtracting totalizer at all times register the complement, less "one" of the amount registered on the adding wheels 104, let it be assumed that 25 the two sets of wheels register:

Positive-----	00250.00
Negative-----	99749.99

An amount, greater than \$250.00, let us say 30 \$255.00, will now be subtracted from the \$250.00 standing on the positive totalizer wheels 104. Subtraction is accomplished by adding the amount \$255.00, to be subtracted, onto the negative totalizer wheels.

35 In the machines of the prior art referred to, the totalizer wheels would now stand at:

Positive-----	99995.00
Negative-----	00004.99

40 However, in the present invention, when the amount of \$255.00 was added onto the negative totalizer wheels 105, the highest order negative wheel 105 was advanced from its "9" to its "0" position, thereby causing the positive wheel 104 of this order, and consequently the tooth 117 rigidly connected thereto, to pass from its "zero" position to its "9" position, which, as above described, rocks the arm 164 clockwise, and through the transmitting 45 shaft 151, trips the units transfer device, causing the units order negative totalizer wheel 105, now engaged with the actuator, to advance one step. At the end of the operation, the totalizer wheels register the following:

Positive wheels-----	99994.99
Negative wheels-----	00005.00

50 which latter amount is the correct negative balance.

With the adding and subtracting totalizer registering the above amounts, the positive wheels 104 are next selected, and an amount greater than \$5.00 is added thereon. Assuming that the amount added is \$10.00, as the

positive wheel 104 of the highest order passes from its "9" position, in which it was left, to its "zero" position, the tooth 117 likewise moves from its "9" position (Fig. 9) to its "zero" position (Fig. 8), and, since, when the positive wheels were selected for engagement with the actuator racks 64, the tooth 117 was moved into cooperative relation with the finger 184 projecting upwardly from the arm 166, the tooth 117 as it wipes the finger 184, in passing from "9" to "0", rocks this arm clockwise, and, due to the train of reversing gears coupling the arm 166 and the arm 164, the latter arm is rocked counter-clockwise, to rock the bell crank lever 161 clockwise. The bell crank lever 161, in turn, wipes the stud 160 in the arm 159 to rock the shaft 151 counter-clockwise and trip the units transfer device to cause "1" to be added onto the units positive totalizer wheel. The positive totalizer wheels now register the correct balance, that is \$5.00.

55 One more example will be given to illustrate that the correct balance is always obtainable on a machine provided with this novel device.

60 Heretofore, in machines of this type, after the negative set of totalizer elements 105 was restored to zero and, as a consequence, the positive set of wheels 104 were left standing "nine", it was necessary to perform a blank operation to restore the positive set of wheels to zero before an amount could be added thereon.

65 Let it be assumed that the negative wheels 105 of the totalizer have been reset to zero. When this has occurred, the positive totalizer wheels 104 are all standing at "9". With the totalizer standing in this position, it is desired to add an amount, let us say \$12.00, 70 on the positive side of the totalizer. In adding \$12.00 to the positive wheels 104, the units of cents and tens of cents wheels are not disturbed. The "12" is added to the units of dollars and tens of dollars wheels, advancing 75 both these wheels to "1" and advancing the wheels to the left of the tens of dollars wheel from their "9" to their "zero" positions. As the positive wheel 104 of highest order passes 80 from "9" to "zero", the tooth 117 trips the units transfer device to add "one" to the positive units wheel, so that the operation will 85 have proceeded as follows:

Positive wheels-----	99,999.99
Negative wheels-----	00,000.00

90 Add \$12.00 to positive wheels,

Positive wheels-----	00,011.99
Negative wheels-----	99,988.00

95 Add "1" by units transfer to units wheel of positive set

Positive wheels-----	00,012.00
Negative wheels-----	99,987.99

The positive wheels 104 now stand at \$12.00, which is the correct amount.

The above is also true when the positive set of wheels has been restored to zero and it is desired to add an amount onto the negative set of wheels.

Enforced selection of proper totalizer when taking totals

10 Means is provided in the present machine to compel the operator to take the balance from the proper set of totalizer wheels of the adding and subtracting totalizer. This means takes the form of a locking mechanism which operates in connection with the "add" key 41 (Fig. 4) and the "subtract" key 42 in such a manner that when there is a positive balance on the adding wheels 104, it is impossible to depress the "subtract" key 42, and when there is a true negative balance on the subtracting wheels 105, it is impossible to depress the "add" key 41.

The keys 41 and 42 when depressed, are held in such positions by means of a well known locking detent bar, not shown herein, but which is shown and described in the above mentioned patents, and when the keys are released near the end of the operation, they return to their normal positions under the influence of springs, not shown.

25 The locking device to compel the operator to take a balance from the proper set of totalizer wheels, is operated by the means which trips the transfer device for the units 30 totalizer wheels, and is controlled by the well-known total control lever 39 (Fig. 2).

One form of such locking device includes a locking sector 185 (Fig. 4) carried by an arm 186 pivotally mounted on a stud 187 in the 40 supporting hanger 69 and a similar hanger 89 (Fig. 7) omitted from Fig. 4 for clearness. The "add" key 41, when depressed, forces a stud 188 thereon against an inclined face 189 on the sector 185 to rock the sector 45 and its arm 186 clockwise about the stud 187.

Similarly, the "subtract" key 42, when depressed, forces a stud 190 thereon, against an inclined face 191 on the sector 185. The face 191 is inclined in the opposite direction from 50 the face 189, for which reason, the "subtract" key rocks the sector 185 counter-clockwise about the stud 187.

The sector arm 186 (Fig. 4), which, with 55 its sector, normally occupies a neutral position, is under spring tension in both clockwise and counter-clockwise directions, and, as explained above, may be rocked in either direction from its neutral home position by the keys 41 or 42. Upon release of the 60 pressed key 41 or 42, the sector 185 and its arm 186 are restored to neutral or home position by one or the other of two springs 201 and 202. The spring 202 holds one arm 203 of a bell crank 204, pivoted on the stud 187, 65 in contact with a stud 205 in the hanger 69,

the remaining arm 211 of the bell crank 204 having a stud 206 extending across that edge of the sector arm 186 farthest from the stud 205. The spring 201 is connected to and holds the sector arm 186 in contact with the stud 206 on the arm 211 of the bell crank 204.

70 The key 42 (Fig. 4) when depressed, rocks the sector 185 and its arm 186 counter-clockwise, but, since the arm 203 of the bell crank 204 abuts against the stationary stud 205, the bell crank cannot move in a counter-clockwise direction from the position shown in Fig. 4, for which reason counter-clockwise movement of the arm 186 tensions the spring 201, which, when the key 42 is released, restores the 75 arm 186 and the sector 185 to neutral position, as shown. The key 41, when depressed, rocks the sector 185 and its supporting arm 186 clockwise, and, since the arm 186 abuts against the stud 206 in the arm 211 of the 80 bell crank 204, the bell crank rocks counter-clockwise, thereby tensioning the spring 202, which, when the key 41 is released near the end of the operation, restores the sector 185, its supporting arm 186 and the bell crank 204 85 to the positions shown in Figure 4.

85 Since the adding and subtracting totalizer is concealed within the machine, the operator will not know at the end of a series of adding and subtracting operations, whether the resulting balance on the totalizer is positive or negative. If it is a positive balance it will be registered on the adding wheels 104, whereas if it be a negative balance it will be registered on the subtracting wheels 105. 90 And in order to enable the operator when taking a total or sub-total of such balance, be it positive or negative, to select the proper key 41 or 42 which will set the machine so as to bring the desired set of wheels 104 or 105 95 into alignment with the actuators 62, 63, the adding and subtracting totalizer is arranged to control means which automatically locks against depression that key 41 or 42 which corresponds with the set of wheels which does 100 not bear the correct balance.

105 The arm 186 (Fig. 4) has an upwardly extending projection 192 having an opening 193 (see also Fig. 6), formed of a vertical slot and a horizontal slot connected therewith, through which projects a stud 194 on a link 195 pivoted on the end of an arm 196 pinned to a suitably supported shaft 197 (see also Fig. 13). The stud 194 also projects through a slot 198 (Fig. 7), in one arm 199 of a bell 110 crank 199, 200 pivoted on the stud 187.

115 The arm 200 of the bell crank, when in the position shown in Figs. 4 and 7, is normally held against movement by a stud 212 in the link 195 which seats in a notch in the hanger 89 (Fig. 7) and prevents the link 195 from 120 rocking on its pivotal connection with the arm 196.

125 The stud 194 normally lies in the horizontal part of the opening 193, thereby permit- 130

ting the sector-supporting arm 186 to rock in either direction without affecting the bell crank arm 200, when either key 41 or 42 is depressed to select wheels 104 or 105 for engagement with the actuator racks 64.

The free end of the bell crank arm 200 is recessed to form prongs 213, 214 embracing a locking disk 215 (see also Fig. 5) pivoted on a stud 216 in the hanger 69. The periphery of the locking disk 215 is reduced or cut away partway therearound in such a manner that when the reduced surface 217 is opposite the prong 214, the unreduced periphery of the disk is in line with the prong 213, thereby permitting clockwise movement of the arm 200, but preventing counter-clockwise movement thereof. When the locking disk 215 is rocked counter-clockwise, as will be described hereinafter, the unreduced periphery will be positioned opposite the prong 214 and the reduced portion 217 brought to a position opposite the prong 213, thereby permitting counter-clockwise movement of the arm 200 and preventing the clockwise movement thereof.

As mentioned above, the stud 212 in the link 195 normally holds the arm 200 in its neutral position and the stud 194 is normally intermediate the ends of the horizontal part 30 of the opening 193 in the branch 192 of the sector-supporting arm 186, thereby permitting the arm to move freely in either direction independently of the arm 200. The locking disk 215 is, therefore, ineffective to lock the keys 41 and 42 against depression on adding operations.

When a total is to be taken from the adding and subtracting totalizer, however, it is desired to lock against depression that key 41 or 42, which selects the totalizer wheels bearing the complement of the true balance, or, to state it another way, to enforce the depression of the key 41 or 42 which selects the totalizer wheels on which the correct balance is registered.

In order to provide means for determining which totalizer selecting key 41 or 42 shall be depressed, it is first desirable to connect the key operated mechanism, as the sector 185 and its arm 186, with the variable locking mechanism, as the bell crank 199, 200, and further, to place the locking mechanism under control of the adding and subtracting totalizer.

The connection between the key-operated mechanism and the variable locking mechanism is accomplished by first adjusting the total control lever 39 (Fig. 2), the body portion of which has a cam slot 220 formed thereinto to accommodate a stud 218 carried on an arm 219 fast on the end of the shaft 197 which also carries the lifting arm 196 (Fig. 4).

The stud 218 normally lies intermediate the ends of the cam slot 220 in an enlargement 65 thereof. The total control lever 39 when

shifted in either direction from its normal intermediate or "add" position causes the wall of the cam slot 220 to rock the arm 219 and its shaft 197 in clockwise direction (Fig. 2) to rock the arm 196 clockwise and draw the link 195 upwardly, thereby displacing the locking stud 212 (Fig. 7) from its seat in the hanger 89, and positioning the connecting stud 194 in the vertical branch (Fig. 6), of the inverted T-shaped slot 193 formed in the arm 192 connected to the sector-supporting arm 186. The connecting stud 194 when thus adjusted is still embraced by the slot 198 (Fig. 7), in the arm 199 of the bell crank 199, 200.

The variable locking mechanism is controlled by the adding and subtracting totalizer by extending the transmitting shaft 151, rocked by the tripping disk 116 (Fig. 8) and tooth 117, beyond the totalizer of lowest order (Fig. 13) to a point adjacent the locking disk 215. An arm 236 (see Figs. 4 and 5) fast on the shaft 151 carries a stud 235 which, in the normal idle positions of the parts, lies apart from the locking disk 215, as shown, but when the totalizer wheels are engaged with their actuators 62, 63, the shaft 151 with its arm 236 and stud 235 shifts to position the stud as shown in dotted lines in Fig. 4, adjacent a finger 238 projecting radially from a disk 226 journaled on the stud 216 mounted in and projecting on both sides of the hanger 69, on which stud the locking disk 215 is journaled.

A gear 225 (Fig. 13), fast on the disk 226 meshes with a wide pinion 227 (Fig. 4), pivoted on a stud 228 mounted in an ear 229 of a hanger 69, which latter meshes with a second wide pinion 222 likewise pivoted on a stud 223 on the ear 224. The last-named wide pinion 222 is also in mesh with a gear 221 fast on the locking disk 215 which latter also carries a radially projecting finger 237.

The gears 225 and 221, and the pinions 227 and 222 constitute a reversing gear similar to that associated with the arms 164, 166 (Fig. 8) so that rotation of the disk 226 in one direction will rock the locking disk 215 in the opposite direction and vice versa.

The stud 235 (Fig. 13) extends across the plane of one or the other but not both of the fingers 237 or 238 on any operation of the machine. If the adding and subtracting totalizer is shifted longitudinally to select the negative totalizer wheels 105 for engagement with the actuator racks 64, the stud 235 of the arm 236 extends across the plane of the finger 238 on the disk 226, but when the positive totalizer wheels 104 are shifted opposite the actuator racks 64, the transmitting shaft 151 and arm 236 are moved therewith to the left to position the stud 235 across the plane of the finger 237 on the locking disk 215.

Assuming that an amount is on the positive totalizer wheels 104, and, that a larger

amount is to be subtracted therefrom, the totalizer is longitudinally shifted to the position shown in Fig. 13, that is, with the negative wheels 105 in line with the actuator racks 64. After the actuator racks are positioned under control of the amount keys 40 (Fig. 1), the negative wheels 105 of the totalizer are engaged therewith, such engagement positioning the stud 235 (Figs. 4, 5 and 13), of arm 236 in co-operative relation with the finger 238 on the disk 226. The actuator racks 64 are then restored to their normal positions, thereby accumulating upon the negative totalizer wheels 105 the amount which was to be subtracted from the positive wheels 104. At the same time, the positive wheels 104 are turned backwardly. The amount thus subtracted from the positive wheels 104 being greater than the amount already thereon, the tripping tooth 117 (Fig. 8) turns in reverse direction through the "zero" position, and thereby rocks the arm 164, bell crank 161 and the transmitting shaft 151, as explained above. As the finger 181 on the bell crank 161 (Fig. 8) rocks the shaft 151 counter-clockwise, the arm 236 (Fig. 4) and the stud 235 thereon are likewise rocked counter-clockwise, and since the stud 235 was positioned as shown in dotted lines in Fig. 4, the counter-clockwise movement thereof rocks the finger 238 and the disk 226 clockwise about the stud 216 which, due to the train of reversing gears described above, will rock the locking disk 215 counter-clockwise to position the unmutilated periphery thereof in the path of the prong 214 on the arm 200. With the locking disk 215 in this position, the arm 200 and the arm 186 which carries the sector bar 185, are locked against movement in a clockwise direction, but since the recessed or mutilated part 217 of the disk 215 has been brought opposite the prong 213 of the arm 200, the latter, together with the arm 186, are free to move counter-clockwise. The locking disk 215, therefore, locks the "add" key 41 (Fig. 4) against depression, and frees the "subtract" key 42. Since, on total taking operations, it is necessary to press one of the keys 41 or 42, it can be seen that with the negative balance on the adding and subtracting totalizer, the "subtract" key must be depressed in order to select the negative totalizer wheels 105 for restoration to zero.

A stud 240 (Fig. 4) on a spring-pressed retaining pawl 241 engages one of two notches formed in the disk 226 (Fig. 5) to hold this disk and the locking disk 215 in the positions to which they are adjusted.

Depression of the "subtract" key 42 at this time forces the stud 190 thereon into contact with the inclined edge 191, as described above, to shift the sector bar 185 and the arm 186 counter-clockwise, which, due to the connection afforded by the stud 194 between the arm 192 and the arm 199, rocks the arm 200 also counter-clockwise, thereby moving the prong 213 into the recessed portion of the locking disk 215. If the operator attempts to depress the "add" key 41, the stud 188 therein is forced into contact with the incline 189, which tends to rock the sector bar 185, arm 186 and arm 200 clockwise. But clockwise movement of the arm 200, and consequently of the arm 186 and sector bar 185, is prevented by the unmutilated periphery of the locking disk 215 which now lies in the path of the prong 214. The stud 188 on the key 41 will, therefore, be arrested by the sector bar 185 in its partially depressed position, and as soon as the pressure is removed from this key, a spring (not shown) returns it to its normal position.

Obviously, the arm 236 on the transmitting shaft 151 operates the disk 226 and locking disk 215 each time the adding wheel 104 of highest order passes through "zero" in either direction, the disks remaining in the positions to which they were last adjusted until the totalizer passes through its "zero" position in the opposite direction, the transmitting shaft 151 being shifted with the totalizer to position the arm 236 adjacent the fingers 237 or 238 depending upon whether the operation is an addition or a subtraction.

And if the true balance on the totalizer is positive, rather than negative, the parts will be positioned as shown in Fig. 4, wherein the locking disk 215 prevents depression of the "subtract" key 42 and permits depression of the "add" key 41.

The spring 153 (Fig. 3) restores the transmitting shaft 151 and its arm 236 (Figs. 4 and 5), to normal after each operation of the shaft by the totalizer, rocking of the arm 236 being unobstructed by that finger 237 or 238 with which the arm is not aligned. As the arm 236 rocks one of the fingers 237 in clockwise direction, the remaining finger rocks in counter-clockwise direction towards but out of the plane of the arm 236.

Restoration of the total control lever 39 (Fig. 2) to its normal "add" position, returns the link 195 to its normal position, wherein the coupling stud 194 lies in the horizontally extending part of the opening 193 thereby disconnecting arms 192 and 199, and the locking stud 212 again seats in the notch (Fig. 7) in the stationary hanger 89 to enable the selective keys 41 and 42 to freely rock the arm 192 in either direction in selecting the set of adding wheels 104 or 105 to engage the actuators. This adjustment also enables the keys 41, 42 when depressed, to lock the total control lever 39 against operation by shifting one end or the other of the horizontal part of the opening 193 over the coupling stud 192.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed as new is:

1. In a machine of the class described, the combination with an adding and subtracting totalizer having a set of adding elements and a set of subtracting elements; actuators therefor; and a plurality of keys to select the set of elements to be engaged with the actuators; of normally ineffective means to lock against operation that key which selects the adding elements, when the balance is negative, and to lock the subtracting element-selecting key against operation when the balance is positive.
2. In a machine of the class described, the combination with an adding and subtracting totalizer having a set of adding elements and a set of subtracting elements; actuators therefor; and a plurality of keys to select the set of elements to be engaged with the actuators; of normally ineffective means to lock against operation that key which selects the adding elements, when the balance is negative, and to lock the subtracting element-selecting key against operation when the balance is positive; and a total control member to render the locking means effective or ineffective.
3. In a machine of the class described, the combination of an adding and subtracting totalizer having a set of adding elements and a set of subtracting elements; actuators therefor; and means to select which set of elements is to be engaged with the actuators; of normally ineffective means to prevent the selection of the adding elements when the balance is negative, and to prevent the selection of the subtracting elements when the balance is positive; and settable means to control the effectiveness of the locking means.
4. In a machine of the class described, the combination with an adding and subtracting totalizer, having a set of positive elements and a set of negative elements; a set of actuators common to both sets of elements; adjustable means to select either set of elements for operation; and a total control mechanism; of normally idle locking mechanism; means controlled by the total control mechanism to render the locking mechanism effective; and means controlled by the adding and subtracting totalizer to set the locking mechanism to enforce the selection for clearing of that set of elements on which is registered the true balance.
5. In a machine of the class described, the combination with an adding and subtracting totalizer, including a set of positive accumulating elements and a set of negative ac-

cumulating elements; either of which sets may be restored to zero; actuators for said sets of elements; means to select which of said sets of elements shall be restored to zero; and means to condition the machine for restoring the selected set of elements to zero; of normally ineffective locking means for the selecting means; and means controlled by the highest order totalizer element as the balance passes from positive to negative and vice versa to prevent the selection of any but that set of elements bearing the true balance.

6. In a machine of the class described, the combination with an adding and subtracting totalizer having a set of positive accumulating elements and a set of negative accumulating elements, either set of said elements being capable of restoration to zero; actuators for said adding and subtracting totalizers; and a plurality of keys to determine which of said sets of totalizer elements shall be restored to zero; of normally ineffective locking means for said keys; means actuated by the highest order totalizer element when the balance passes from positive to negative for locking the positive element-selecting key against depression, and actuated when the balance passes from negative to positive to lock the negative element-selecting key against depression; and a manually operable member to prepare the machine for total and sub-total taking operations, and render the locking means effective.

7. In a machine of the class described, the combination with an adding and subtracting totalizer, having a set of positive accumulating elements, and a set of negative accumulating elements; actuators therefor; and means to determine which of said sets of accumulating elements shall be engaged with the actuators; of a locking bar for said determining means; a locking mechanism normally ineffective relatively to the locking bar and including a settable member; adjustable means to connect the locking mechanism and the locking bar; and means to automatically position the settable member of the locking means depending upon the nature of the true balance registered on the adding and subtracting totalizer.

8. In a machine of the class described, the combination with an adding and subtracting totalizer having a set of positive accumulating elements and a set of negative accumulating elements; actuators therefor; the accumulating elements normally disengaged from the actuators; selective means to determine which of the sets of accumulating elements shall shift into engagement with the actuators; a lock for the selective means to prevent the operation of more than one of such selective means; a second locking mechanism normally ineffective relatively to the first-named lock, and including an adjustable locking member; means operable at will to

connect or disconnect the two locking mechanisms; and means to automatically adjust the locking member depending upon the nature of the balance registered on the adding and subtracting totalizer.

- 5 9. In a machine of the class described, the combination with an adding and subtracting totalizer, having a set of positive accumulating elements and a set of negative accumulating elements; actuators therefor; and manipulative keys to determine which of said sets of accumulating elements shall shift into engagement with the actuators; of a locking bar for said keys; an arm actuated by the bar, 70
10 and normally disconnected therefrom; adjustable means to releasably connect said bar with said arm; an adjustable locking disk adapted in one of its positions to lock the arm against movement in one direction, and in 75
15 its other position to lock said arm against movement in the opposite direction; and means to position the locking disk.
- 20 10. In a machine of the class described, the combination with an adding and subtracting totalizer having a set of positive accumulating elements and a set of negative accumulating elements; actuators therefor; keys to determine which of said sets of accumulating elements shall shift into engagement 80
25 with the actuators; and a locking bar for said keys adapted to be moved in either of two directions, depending on which of said keys is depressed; of an arm having a recess formed in the end thereof, said arm being normally 85
30 disconnected from said bar, and normally locked against movement; manually operable means adapted to unlock the arm and connect it with the locking bar; a locking disk associated with the recess in the locking arm to 90
35 control the direction of movement of said arm, thereby locking one of said keys against 95
40 depression; and means under control of the adding and subtracting totalizer to position the locking disk to lock one of the keys
45 against depression.

11. In a machine of class described, the combination with an adding and subtracting totalizer, having a set of positive accumulating elements and a set of negative accumulating element; actuators therefor; a plurality of keys to select which of said sets of totalizer elements shall be engaged with the actuators; a normally ineffective locking bar for said keys; means to render said locking bar effective on total and sub-total taking operations; a locking member, the position of which controls the direction in which the locking bar can shift, to determine which of said keys shall be locked against depression; and means 105
50 actuated by the totalizer element of highest order when the balance changes from positive to negative or from negative to positive, to shift the locking member to a position corresponding to the set of totalizer elements 110
55 on which the true balance is registered, and
60
65

to lock against depression the key for selecting the set of totalizer elements upon which the complementary balance is registered.

12. In a machine of the class described, the combination of an adding and subtracting 70
totalizer having a set of positive accumulating wheels and a set of negative accumulating wheels; keys to control the selection of said sets of totalizer wheels; and means controlled by said sets of accumulating wheels to prevent depression of one the keys. 75

13. In a machine of the class described, the combination of an adding and subtracting totalizer, including a set of positive accumulating wheels and a set of negative totalizer 80
wheels; a plurality of keys to control the selection of the sets of accumulating wheels; means normally ineffective to lock the keys against depression; and means operable when preparation is made to restore one of the sets of accumulating wheels to zero, to render said locking means effective to prevent depression of one of the keys. 85

14. In an adding machine, the combination with a plurality of sets of adding wheels; 90
actuators therefor; the sets of adding wheels adapted to move into and out of engagement with the actuators; selective means to determine which of the sets of adding wheels shall engage with the actuators; and a manipulative member; of a variable locking mechanism to determine which of the selective means shall be operative; a shiftable device operable by the selective means; and a coupling controlled by the manipulative member 95
100 to connect the shiftable device and the locking mechanism against idle relative movement.

15. In an adding machine, the combination with a plurality of sets of adding wheels; 105
actuators therefor; the sets of adding wheels adapted to move into and out of engagement with the actuators; selective means to determine which of the sets of adding wheels shall engage with the actuators; and a manipulative member; of a variable locking mechanism to determine which of the selective means shall be operative; a shiftable device operable by the selective means; a coupling controlled by the manipulative member to 110
115 connect the shiftable device and the locking mechanism against idle relative movement; and a transmitting member operable by the adding wheels, to adjust the variable locking mechanism according to the condition of the adding wheels. 120

16. In an adding machine, the combination with a plurality of sets of adding wheels; 125
actuators therefor; the sets of adding wheels adapted to move into and out of engagement with the actuators; selective means to determine which of the sets of adding wheels shall engage with the actuators; and a manipulative member; of a variable locking mechanism to determine which of the selective means 130

shall be operative; a shiftable device operable by the selective means; a coupling controlled by the manipulative member to connect the shiftable device and the locking mechanism against idle relative movement; a transmitting element operable by the adding wheels according to their condition; and a reversing gearing connected to the locking mechanism, either side of which reversing gearing is operable by the transmitting element to adjust the locking mechanism according to the condition of the adding wheels.

17. In an adding machine, the combination with a plurality of sets of adding wheels; actuators therefor; the sets of adding wheels adapted to move into and out of engagement with the actuators; selective means to determine which of the sets of adding wheels shall engage with the actuators; and a manipulative member; of a variable locking mechanism to determine which of the selective means shall be operative; a shiftable device operable by the selective means; a coupling controlled by the manipulative member to connect the shiftable device and the locking mechanism against idle relative movement; a transmitting element operable by the adding wheels according to their condition and shiftable with the adding wheels as the latter shift into and out of engagement with the actuators; an arm on the transmitting element; a train of reversing gearing connected to the locking mechanism; and a finger on the respective opposite ends of the train of gearing, the fingers lying in different vertical and transverse planes, the arm on the transmitting element adapted to coact with either finger to adjust the locking mechanism according to the condition of the adding wheels.

18. In an adding machine, the combination with a plurality of sets of adding wheels; actuators therefor; the sets of adding wheels adapted to move into and out of engagement with the actuators; selective means to determine which of the sets of adding wheels shall engage with the actuators; and a manipulative member; of a variable locking mechanism to determine which of the selective means shall be operative; a shiftable device operable by the selective means; a coupling controlled by the manipulative member to connect the shiftable device and the locking mechanism against idle relative movement; a transmitting element operable by the adding wheels according to their condition, to shift the locking mechanism alternately in opposite directions.

19. In an adding machine, the combination with a plurality of sets of adding wheels; actuators therefor; the sets of adding wheels adapted to move into and out of engagement with the actuators; selective means to determine which of the sets of adding wheels shall

engage with the actuators; and a manipulative member; of a variable locking mechanism to determine which of the selective means shall be operative; a shiftable device operable by the selective means; a transmitting element operable by the adding wheels according to their condition, and shiftable with the adding wheels relatively to the locking mechanism, to adjust the locking mechanism alternately in opposite directions depending upon the condition of the adding wheels and adapted to restore to normal position after each adjusting operation.

20. In a machine of the class described, the combination with a plurality of sets of adding wheels; actuators therefor; the adding wheels normally disengaged from the actuators; selective means to determine which of the sets of adding wheels shall engage the actuators; and a manipulative member; of a variable locking mechanism controlled by the adding wheels to determine which of the selective means shall be operative; a normally ineffective connection between the locking mechanism and the selective means; and means controlled by the manipulative member to render the connection effective or ineffective.

21. In a machine of the class described, the combination with a plurality of sets of adding wheels; actuators therefor; the adding wheels normally disengaged from the actuators; selective means to determine which of the sets of adding wheels shall engage the actuators; and a manipulative member; of a variable locking mechanism controlled by the adding wheels to determine which of the selective means shall be operative; and a connection between the locking mechanism and the selective means, including a normally ineffective coupling between the connection and the locking mechanism, controlled by the manipulative member.

22. In a machine of the class described, the combination with a plurality of sets of adding wheels; actuators therefor; the adding wheels normally disengaged from the actuators; selective means to determine which of the sets of adding wheels shall engage the actuators; and a manipulative member; of a variable locking mechanism controlled by the adding wheels to determine which of the selective means shall be operative; and normally ineffective connecting means between the locking mechanism and the selective means, and operable by the selective means, the connection including a combined coupling and retaining means controlled by the manipulative member.

23. In a machine of the class described, the combination with a plurality of sets of adding wheels; actuators therefor; the adding wheels normally disengaged from the actuators; selective means to determine which of the sets of adding wheels shall engage the ac-

tuators; and a manipulative member; of a variable locking mechanism controlled by the adding wheels to determine which of the selective means shall be operative; an armoperable by the selective means; a normally ineffective coupling between the arm and the locking mechanism, and controlled by the manipulative member; and a normally effective retaining means also controlled by the manipulative member.

24. In a machine of the class described, the combination with a plurality of sets of adding wheels; actuators therefor; the adding wheels normally disengaged from the actuators; selective means to determine which of the sets of adding wheels shall engage the actuators; and a manipulative member; of a variable locking mechanism controlled by the adding wheels to determine which of the selective means shall be operative, the locking mechanism having a slot; a connection between the locking mechanism and the selective means having an opening, one branch of which registers with the slot in the locking mechanism; and a coupling element extending through the slots and adjustable by the manipulative member into and out of the registering portions of the slot and opening.

25. In a machine of the class described, the combination with a plurality of sets of adding wheels; actuators therefor; the adding wheels normally disengaged from the actuators; selective means to determine which of the sets of adding wheels shall engage the actuators; and a manipulative member; of a variable locking mechanism controlled by the adding wheels to determine which of the selective means shall be operative; a connection between the locking mechanism and the selective means, including a normally ineffective coupling between the connection and the locking mechanism, controlled by the manipulative member; and a retaining device to hold the locking mechanism inactive while the connection between the selective means and the locking mechanism is ineffective.

26. In a machine of the class described, the combination of an adding and subtracting totalizer, including a set of positive wheels and a set of negative wheels; a segment normally ineffective to actuate the units order wheel; means to render the segment effective to advance the units order wheel a single step; a member movable in either direction to operate said means; and means intermediate the totalizer wheel of highest order and the member to actuate said member.

27. In an adding and subtracting totalizer, the combination of a transmitting element; a drive member associated with the units order totalizer wheel; means controlled by the transmitting element to permit the drive member to turn the units order totalizer wheel a single step; rocking arms; reversing

gearing coupling the arms; means connected to one of said arms and operable in opposite directions to actuate the transmitting element, and means controlled by the highest order totalizer wheel to actuate one or the other of said arms when said highest order totalizer wheel passes the zero point in either direction.

28. In an adding and subtracting totalizer; the combination of a transmitting element intermediate the totalizer wheels of highest and lowest order; normally ineffective means, including a drive member, to turn the totalizer wheel of lowest order a single step; means actuated by the transmitting element to render the drive member effective; means operable in either direction to rock the transmitting element; rocking arms; a train of reversing gearing coupling the arms for actuating said means; and means controlled by the totalizer wheel of highest order to rock one or the other of the arms when said highest order totalizer wheel passes the zero point in either direction.

29. In a machine of the class described, the combination with an adding and subtracting totalizer shiftable axially to either of two positions; means, including a drive member to turn the totalizer wheel of lowest order a single step; a transmitting element to render the drive member effective, and shiftable with the totalizer; means to rock said transmitting element in one direction regardless of the position to which it is shifted; and means actuated by the totalizer wheel of highest order as it passes the zero point in either direction to actuate the last-named means.

30. In a machine of the class described, the combination with an adding and subtracting totalizer; actuators therefor with which the totalizer engages and disengages; and a normally ineffective drive means to turn a totalizer wheel of lower value one step; of means controlled by a totalizer wheel of higher value to control the one-step rotation of the totalizer wheel of lower value, including a transmitting element shiftable bodily with the adding and subtracting totalizer, and extending between the totalizer wheels of higher and lower orders; means controlled by the totalizer wheel of higher value to operate the transmitting element in one direction subsequently to the engagement of the totalizer with the actuators; and means actuated by the transmitting element to render the drive means effective.

31. In a machine of the class described, the combination with an adding and subtracting totalizer; and drive means normally ineffective to turn a totalizer wheel of lower value one step; of means controlled by a totalizer wheel of higher value to control the one-step rotation of the totalizer wheel of lower value, including a transmitting element extending between the totalizer wheels; means actuated

- by the transmitting element to render the drive means effective; an actuating member on the totalizer wheel of higher order; and a leverage operated by the actuating member 5 to shift the transmitting element.
32. In a machine of the class described, the combination with an adding and subtracting totalizer; and drive means normally ineffective to turn a totalizer wheel of lower value 10 one step; of means controlled by a totalizer wheel of higher value to control the one-step rotation of the totalizer wheel of lower value, including a transmitting element extending between the totalizer wheels; means actuated 15 by the transmitting element to render the drive means effective; an actuating member on the totalizer wheel of higher order; rocking arms alternately operated by the actuating member; reversing gearing connecting 20 the arms; and a lever connected to one of the arms and rocked in opposite directions by the arms to shift the transmitting element in one direction, irrespective of the direction in which the lever rocks.
33. In a machine of the class described, the combination with an adding and subtracting totalizer, including a series of positive totalizer wheels and a series of negative totalizer wheels; actuators for the wheels; the totalizer 30 normally disengaged from the actuators, and shiftable into and out of engagement therewith and axially relatively thereto; of means controlled by a totalizer wheel of higher value to turn a totalizer wheel of lower value one 35 step, including a drive member; a transmitting element extending between the said totalizer wheels; a lever operated by the transmitting element to render the drive member effective; an actuating member associated 40 with the totalizer wheel of higher value; rocking arms alternately operated by the actuating member, the rocking arms lying in different vertical and horizontal planes; reversing gearing connecting the arms; a lever 45 connected to one of the arms and rocked alternately in opposite directions to shift the transmitting element in a single direction; and means to restore the transmitting element and the first-named lever to normal after each 50 operation of the second-named lever, the transmitting element and its first-named lever shiftable with the totalizer and normally in ineffective relation to the second-named lever and the drive member, respectively.
34. In an adding and subtracting totalizer, the combination with a drive member to impart a single step of rotation to a totalizer wheel of lower order; of an axially shiftable actuating member associated with a 55 totalizer of higher order; rocking arms alternately operated by the actuating member; reversing gearing connecting the arms to bring one of said arms into operative position as another of said arms is operated; a transmitting element extending between the 60 totalizer wheels of higher and lower orders, and shiftable in one direction to control the operation of the drive member and in another direction as a preliminary to another control movement thereof; means operated by the arms to shift the transmitting element in said one direction, irrespective of the direction of movement of said means; and means to shift the transmitting element in its other direction. 70
35. In an adding and subtracting totalizer, the combination with a drive member to impart a single step of rotation to a totalizer wheel of lower order; of an actuating member associated with a totalizer wheel of higher order; rocking arms alternately operated by the actuating member; reversing gearing connecting the arms; a lever connected to one 75 of the arms and operable alternately in opposite directions; a transmitting element between the totalizer wheels of higher and lower orders; and an arm on the transmitting element removably positioned in the path of travel of the lever and rocked thereby together with the transmitting element to control the operation of the drive member for the totalizer wheel of lower order. 80
36. In an adding and subtracting totalizer, the combination with a drive member to turn a totalizer wheel of lower order one step; of an actuating member associated with a totalizer wheel of higher order; a transmitting element extending between the totalizer wheels of higher and lower order; an arm 85 on the transmitting element adjacent the totalizer of higher value; means alternately travelling in opposite directions to rock the arm and the transmitting element to control the operation of the drive member and means intermediate the actuating member and the last-named means, and operated by the actuating member to shift the first-named means alternately in opposite directions as the nature of the true balance on the totalizer changes. 90
37. In a machine of the class described, the combination with an adding and subtracting totalizer; and drive means normally ineffective to turn a totalizer wheel of lower value one step; of a transmitting element extending 95 between the totalizer wheels; means controlled by the totalizer wheel of higher value to operate the transmitting element in one direction; means actuated by the transmitting element to render the drive means effective; and means to operate the transmitting element in another direction after each operation. 100
38. In a machine of the class described, the combination with an adding and subtracting totalizer shiftable axially to either of two positions; of means, including a drive member to turn the totalizer wheel of lowest order a single step; means shiftable with the totalizer to control the operation of the drive 105 110

member when the totalizer is in either of its two positions of adjustment; mechanism to rock said shiftable means in one direction when the latter is in any of its positions; and means actuated by the totalizer wheel of highest order as it passes the zero point in either direction to operate said mechanism.

In testimony whereof I affix my signature.
BERNIS M. SHIPLEY.
